UNITED STATES PATENT OFFICE.

HERBERT H. HILLMAN, OF GRAND HAVEN, MICHIGAN, ASSIGNOR TO CHALLENGE REFRIGERATOR COMPANY, OF GRAND HAVEN, MICHIGAN, A CORPORATION OF MICHIGAN.

BRACKET.

1,278,928.

Specification of Letters Patent. Patented Sept. 17, 1918.

Application filed November 5, 1917. Serial No. 200,303.

To all whom it may concern:

Be it known that I, HERBERT H. HILLMAN, a citizen of the United States, residing at Grand Haven, in the county of Ottawa and State of Michigan, have invented new and useful Improvements in Brackets, of which the following is a specification.

The present invention relates to brackets, such as are suitable for supporting shelves and the like, and its object is to provide an improved bracket and means for readily and securely attaching the same to a support, as the wall of a refrigerator; and more particularly, to provide a bracket having a portion adapted to abut against one side of the support and having a portion adapted to extend through an orifice in the support, together with a fastening member having forks adapted to straddle said extending portion on the other side of the support and to wedgingly press the bracket against the support; and more particularly, to form said member of such material that its forks may be bent toward each other in such manner as to hold the fastener in its operative position against accidental displacement.

The object of this invention, as thus broadly defined, may be attained by various mechanical means and by the cooperation of variously constructed parts: a preferable embodiment of the invention however, is seen in the structure hereinafter described and illustrated by the accompanying drawings, in which:-

Fig. 1 is a fragmentary view in perspective of a support, as the inner wall of a refrigerator, with a shelf held on brackets;

Fig. 2 is a face view of a portion of said support, showing the orifice therethrough and the end of the bracket being inserted into the orifice;

Fig. 3 is a top or plan view of the bracket showing means for fastening the same to the support;

Fig. 4 is a side view of the same;

Fig. 5 is a view of the fastener showing its forks bent into securing position;

Fig. 6 is a side or edgewise view of the fastener; and

Fig. 7 is a front or face view of the same. The support 1, as the inner wall of a re-

frigerator for example, has orifices 2 therethrough. The brackets 3 adapted to support the shelf 4 have portions adapted to abut against one side, as 5, of the support, 55 being the inner side of the refrigerator's wall. These abutting portions, as shown, are the shoulders 6 oppositely disposed and adapted to abut against said inner side of the support adjacent the opposite sides respectively of the orifice. The brackets have also a portion 7 adapted to extend through the orifices. As shown, the sides 8, 9 of the portion 7 are mutually convergent toward the shoulders. When the portion 7 of the bracket, having been turned diagonally of the orifice in order to be thrust through the same as shown in Fig. 2, is turned to the position shown in the other figures, a fastener 10 having forks 11, 12 is driven over 70 the portion 7 on the outer side 13 of the wall, straddling the portion 7 and embracing its opposite sides 8, 9. This fastener wedgingly presses or draws the shoulders 6 against the inner side of the wall, as the 75 fastener is driven or adjusted to its operative position, as by the inclined faces 15 of the forks as seen in Figs. 4 and 6, or by the convergence of the forks toward each other as seen in solid lines in Fig. 7, or by bending the forks toward each other after the fastener is placed in straddling position, as seen in Fig. 5, whereupon the forks engaging the inclined sides 8, 9 draw or press the shoulders 6 into their abutting relation with 80 the inner side 5 of the support. The fasteners being of bendable material, the forks may be bent toward each other as shown to prevent their accidental displacement. The bracket may manifestly be quickly and 85 readily placed in position and thereupon rigidly and securely held in such position by the forked fastener.

The invention being intended to be pointed out by the claim, is not to be limited to 90 or by details of construction shown in the drawings or described in the body of this specification.

I claim:

In a device of the character described; a 100 support having an orifice therethrough; a bracket having a portion adapted to abut

against one side of the support, and a portion adapted to extend through the orifice and having its sides mutually convergent inwardly; a fastener having forks adapted to straddle said last named portion on the other side of the support and to be bent toward each other to press said first-named

portion against the support and to securely hold the fastener and the bracket in operative position.

10

In testimony whereof I have hereunto set my hand at Grand Rapids, Michigan, this third day of November 1917.

HERBERT H. HILLMAN.
